CLAIM

The ornamental design for a housing for an electrical distribution panel, as shown and described.

DESCRIPTION

FIG. 1 is a perspective view of our housing for an electrical distribution panel;

FIG. 2 is a top plan view thereof;

FIG. 3 is a front side elevation view thereof;

FIG. 4 is a left side elevation view thereof;

FIG. 5 is a bottom plan view thereof;

FIG. 6 is a rear side elevation view thereof; and,

FIG. 7 is a right side elevation view thereof.
